UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S WRAP.

SPECIFICATION forming part of Design No. 14,461, dated November 27, 1883.
Application filed September 26, 1883. Term of patent 3½ years.

To all whom it may concern:

Be it known that I, MARY TURNER, of the city, county, and State of New York, have invented and produced a new and original Design for a Pattern of a Lady's Wrap, (numbered 8,869;) and I do hereby declare that the engraved prints accompanying this specification convey to any one accustomed to using paper patterns a clear understanding of how a garment made up by the pattern will appear. The design combines narrow sack-fronts, a half-fitted back with its center seam left open

for some distance at the bottom, wide sleeves that fall in deep rounding outline, and a standing collar.

What I claim as my invention, and desire to secure by Letters Patent, is—

The design for a lady's wrap, as shown in the engraved prints accompanying this specification.

MARY TURNER.

Witnesses:

ALFRED FRANCIS,
MARCELLUS CARLETON SHATTUCK.
